PISTON CLOSURE FOR WATERLESS GAS HOLDERS

Friedrich Einbeck and Friedrich Schürmann,
Dortmund, Germany, assignors to the firm Aug.
Klönné, Dortmund, Germany

Application December 17, 1931, Serial No. 581,762,
and in Germany December 27, 1930

14 Claims. (Cl. 48—176)

This invention relates to a piston closure for a waterless gas holder. Piston closures are known in which a sealing ring is carried on an expandable metal ring consisting of a number of segments or parts connected to the edge of the piston and loaded by means of weights or springs.

In the known piston closures, the segments of the metal rings are united firmly and strongly to each other. On account of this the piston closure of the container wall, which is never an exact cylinder, cannot fit exactly.

The principal feature of this invention lies in the fact that the ring segments are separated from each other by perpendicular gaps, which are 15 covered by a circular band of ductile metal, whereby this band is fastened at its upper end between the closure ring and the segments of the metal ring.

Such a piston closure is a substantial improvement over the known piston closures, in that it always can conform to and pass over the container wall exactly.

The subject matter of the invention is illustrated by way of example in the accompanying 25 drawings.

Fig. 1 is a vertical partial section through the closing piston.

Fig. 2 is a side elevation.

Fig. 3 is a plan.

30 Fig. 4 is a vertical partial section through a second form of construction.

Fig. 5 is a side elevation.

Fig. 6 is a plan.

35 Fig. 7 shows, in plan, a further form of construction of the loading of the metal ring.

Figs. 8 and 9 show a horizontal partial section through a detail of the closing piston.

The packing or sealing ring *a* is in the known way pressed against the wall *d* of the container 40 by means of the levers *b* with counterweights *c*.

The packing ring *a* is carried by an expandable metal ring consisting of a number of separate parts or segments *e* arranged alongside or in side-by-side relation to each other. The parts *e* as 45 shown in Figs. 1 and 2 are at their lower end firmly connected to the piston *f*, whilst the upper end, which is provided with a hole, is movable radially on a pin *i* which is carried by a ring *h*.

As shown in Figs. 2 and 3, each lever *b* acts 50 on four ring segments *e*. As shown, however, in Figs. 5 and 6, a special lever can be provided for each ring segment *e*, or again, as shown in Fig. 7, one lever can act on two ring segments.

Owing to the described arrangement, the ring

segments *e* are secured against any vertical movement at the piston *f* (relatively to the piston). Consequently, when the piston rises and falls the ring segments *e* are carried along directly with the packing or sealing ring *a*. An over-length 60 must be given to the ring segments *e* by means of a slight deviation from the vertical, so as to allow of the whole of the packing surface of the packing ring *a* being pressed, even in the case of horizontal movements, outwards, i. e., towards the wall of 65 the container.

The gaps *k* between the individual ring segments *e* are covered over gas-tight by means of a surrounding band *l*. The band *l* is connected gas-tight to the packing ring *a* as well as to the piston 70 *f*. Since the band must be gas-tight, it may consist of rubbered fabric. It may also be made of some ductile metal, such as lead, copper, etc. In addition to this, a band made of rubbered fabric and fitted with a thin metal insertion *m'* can be 75 provided (see Fig. 8) whereby its durability is increased and its impermeability to gas ensured.

In the form of construction shown in Figs. 4 to 6, the lower ends of the ring segments *e* are not connected directly to the piston *f*. On the 80 contrary, the connection is effected indirectly by means of the band *l*.

The upper end of each ring segment *e* is provided with a pulley *m* which is displaceable on a horizontal, radially directed short bar *n*. 85

In this form of construction of the ring, the individual ring segments offer less resistance to their displacement by the lever *b* than is the case in the form of construction shown in Figs. 1 to 3.

As shown in Figs. 5 and 6, each individual ring 90 segment is loaded by means of a special lever *b*. One single lever *b* could, however, load several ring segments, as shown in Fig. 3 and in Fig. 7.

When, as shown in Fig. 4, the lower end of the band *l* is curved, it will be found advisable to give 95 the metal insertion *n'* a corrugated or undulated cross section, as shown in Fig. 9. The corrugations are preferably small dimensioned; they facilitate the beating of the band against the inner edge.

This beating or compression of the band at the inner circumference is necessary, because the circumference of the band at the inner edge, where it is secured to the closing piston (see Fig. 4) is much smaller than at the outer circumference, where the packing ring is mounted. This difference in circumference is equalized by the compression of the corrugations; the elevated portions of the corrugations lie more closely together 105 110 115

at the point where the band is secured to the disc than at the point where the band is secured to the packing ring.

We claim:—

- 5 1. In a piston closure for waterless gas holders
a sealing ring, an expansible metal ring carrying
said sealing ring, levers pressing said sealing ring
against the wall of the holder, said metal ring
consisting of a number of segments separated by
10 vertical gaps from one another, positioned in side-
by-side relation and secured to the piston against
vertical displacement, a surrounding band made
of fabric provided with a metal insertion covering
15 the gaps between said ring segments, said metal
insertion being undulated, the undulations run-
ning in the direction of the circumference.

2. In a piston closure for waterless gas holders
a sealing ring, an expansible metal ring carrying
said sealing ring, levers pressing said sealing
20 ring against the wall of the holder, said metal ring
consisting of a number of segments separated by
vertical gaps from one another, positioned in side-
by-side relation and secured to the piston against
25 vertical displacement, a surrounding band made of
elastic metal covering the gaps between said ring
segments, said metal being undulated, the undulations running in the
direction of the circumference.

3. In a piston closure for waterless gas-holders
30 a sealing ring, an expansible metal ring carrying
said sealing ring, levers pressing said sealing
ring against the wall of the holder, said metal ring
consisting of a number of segments positioned
35 side by side and separated from each other by
vertical gaps, and a surrounding band of ductile
metal, said band covering and sealing off
said gaps and being secured with its upper end
40 between said sealing ring and the segments of
said metal ring.

4. In a piston closure for waterless gas-holders
a sealing ring, an expansible metal ring carrying
said sealing ring, levers pressing said sealing
45 ring against the wall of the holder, said metal ring
consisting of a number of segments arranged
side by side and separated from each other by
vertical gaps, and a surrounding band of fabric
50 provided with a metal insertion, said band cov-
ering and sealing off said gaps and being secured
with its upper end between said sealing ring and
the segments of said metal ring.

5. In a piston closure for waterless gas-holders
a sealing ring, an expansible metal ring carrying
said sealing ring, levers pressing said seal-
55 ing ring against the wall of the holder, said metal
ring consisting of a number of segments arranged
side by side and separated from each other by
vertical gaps, a surrounding band of ductile met-
al, said band covering and sealing off said gaps
60 and being secured with its upper end between
said sealing ring and the segments of said metal
ring, and radial bars on said piston, said bars
carrying the upper ends of said metal ring seg-
ment, and said segments being movable in a ra-
65 dial direction upon said bars.

6. In a piston closure for waterless gas-holders
a sealing ring, an expansible metal ring carrying
said sealing ring, levers pressing said seal-
70 ing ring against the wall of the holder, said metal
ring consisting of a number of segments ar-
ranged side by side and separated from each
other by vertical gaps, a surrounding band of
75 ductile metal, said band covering and sealing
off said gaps and being secured with its upper
end between said sealing ring and the segments
of said metal ring, radial bars on said piston

and pulleys on said bars carrying the upper ends of said metal ring segments.

7. In a piston closure for waterless gas-holders a sealing ring, an expansible metal ring carrying said sealing ring, levers pressing said sealing ring against the wall of the holder, said metal ring consisting of a number of segments arranged side by side and separated from each other by vertical gaps, a surrounding band of ductile metal, said band covering and sealing off said gaps and being secured with its upper end between said sealing ring and the segments of said metal ring, radial bars on said piston, pulleys on said bars carrying the upper ends of said metal ring segments, and brackets carrying said bars and adapted to prevent lifting of said pulleys from said bars.

8. In a piston closure for waterless gas-holders a sealing ring, an expansible metal ring carrying said sealing ring, levers pressing said sealing ring against the wall of the holder, said metal ring consisting of a number of segments arranged side by side and separated from each other by vertical gaps, and a surrounding band of ductile metal, said band covering and sealing off said gaps and being secured with its upper end between said sealing ring and the segments of said metal ring, and said segments and said band being connected at their lower ends firmly and closely with the piston. 95 100 105

9. In a piston closure for waterless gas-holders a sealing ring, an expansible metal ring carrying said sealing ring, levers pressing said sealing ring against the wall of the holder, said metal ring consisting of a number of segments arranged side by side and separated from each other by vertical gaps, and a surrounding band of ductile metal, said band covering and sealing off said gaps and being secured with its upper end between said sealing ring and the segments of said metal ring to provide a gas-tight connection between the sealing ring and the closing piston, and said segments only extending to substantially the lower end of said sealing ring. 110 115

10. In a piston closure for waterless gas-holders
a sealing ring, an expansible metal ring carrying
said sealing ring, levers pressing said sealing ring
against the wall of the holder, said metal ring
consisting of a number of segments arranged side
by side and separated from each other by vertical
gaps, and a surrounding band of ductile metal,
said band covering and sealing off said gaps and
being secured with its upper end between said
sealing ring and the segments of said metal ring,
one lever arm of each pressing lever being forked
and operating on more than one segment of said
metal ring. 120 125 130

11. In a piston closure for waterless gas-holders
a sealing ring, an expandible metal ring carrying
said sealing ring, levers pressing said sealing
ring against the wall of the holder, said metal
ring consisting of a number of segments arranged
side by side and separated from each other by
vertical gaps, and a surrounding band of ductile
metal, said band covering and sealing off said
gaps and being secured with its upper end be-
tween said sealing ring and the segments of said
metal ring, and said metal band being formed
with an undulated sectional outline to obtain
greater flexibility. 145

12. In a piston closure for waterless gas-holders a sealing ring, an expansible metal ring carrying said sealing ring, levers pressing said sealing ring against the wall of the holder, said metal ring consisting of a number of segments positioned side 150

by side and separated from each other by vertical gaps, and a surrounding band of fabric provided with a metal insertion, said band covering and sealing off said gaps and being secured with its upper end between said sealing ring and the segments of said metal ring, and said metal band being formed with an undulated sectional outline to obtain greater flexibility.

13. A movable closure for waterless gas-holders, comprising a piston, a sealing ring, a dilatable ring carrying said sealing ring and levers mounted upon said piston, pressing the sealing ring against the wall of the holder, said dilatable ring consisting of segments suspendingly sustained upon the piston, and a laminated band secured to the piston and interveningly between the seal-

ing ring and segments pliably joining said segments.

14. A movable closure for waterless gas holders, comprising a piston, a sealing ring, a dilatable ring carrying said sealing ring mounted upon said piston, means for normally dilating said dilatable ring to press the sealing ring against the wall of the holder, said dilatable ring consisting of a plurality of segments suspendingly sustained upon the piston, and a flexible band substantially impervious to gas secured to the piston and interveningly between the sealing ring and segments, pliably joining said segments.
